Primary Examiner — Lauren R Calve(74) *Attorney, Agent, or Firm* — Nelson Mullins Riley & Scarborough LLP(57) **CLAIM**

The ornamental design for a container lid as shown and described.

DESCRIPTION

FIG. 1 is a top perspective view of a container lid of the present design;

FIG. 2 is a bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The broken lines in the drawings illustrate portions of the container lid and form no part of the claimed design.

1 Claim, 8 Drawing Sheets(56)
